UNITED STATES PATENT OFFICE.

GEORGE E. COUTANT, OF DECATUR, ILLINOIS.

BUFFER DEVICE FOR RAILWAY CARS.

Application filed February 20, 1925. Serial No. 10,453.

This invention relates to buffer devices for railway cars.

The general purpose of my invention is to provide an improved buffering mechanism including the usual center stem, with side stems of a novel construction which are arranged in such manner as to protect the springs associated therewith, prevent rattling between the parts, to provide a much shorter stem than that usually employed, without sacrificing any of the ordinary advantages, and obviating the necessity for two or more bearings for each side stem by mounting the spring elements associated with the stem between the bearing connections thereof.

A more specific object of the invention is to provide a tubular stem pivotally connected to the buffer plate, and slidably and pivotally connected to the end sill of the car, and disposing a spring within said tube which is compressed upon inward movement of the buffer plate.

Other and further objects of the invention will more clearly appear from the description and claims hereinafter following.

In the drawings forming a part of this specification, Figure 1 is a top plan view, partly in horizontal section, of a buffering device for railroad cars embodying my invention. Figure 2 is a longitudinal vertical section on the line 2—2, of Figure 1. Figure 3 is a longitudinal vertical section through a portion of the car platform, and the side stems of the buffering mechanism, on the line 3—3 of Figure 1; and Figure 4 is a transverse vertical section of the buffering mechanism side stem, and related parts, on the line 4—4 of Figure 3.

Referring to the drawings, the numeral 9 represents the end platform of a passenger car, provided with a pocket 10 for the reception of the central shock absorbing members of the buffering device 11. The central member 11 consists of a shell 12, containing compression resisting mechanism not shown, a buffer cap 14 secured to the carrying arms 15, and a preliminary spring 16, all of which construction may be of any suitable or desired form.

A center buffering stem 17 is provided, such stem engaging at its rear end the central buffering unit, and at its forward end the stem is provided with a semicircular recess 18 adapted for the reception of a rib or pro-

jection 19 which is secured on the inner surface of the buffer plate 20, said center stem being slidably supported in the usual bearing portions 21 provided therefor in the car platform structure. The buffer member 20 is provided on top with a horizontally disposed plate 22 which is adapted to slide beneath the usual threshold plate 23 associated with the platform.

The buffering device is also provided with side stems 24—24, disposed one on either side of the central buffering member, each of the side stems and associated parts being of the same construction, and similar reference numerals will be utilized to describe similar parts of the side stem arrangement. Each of said side stems 24 is in the form of a tubular member, the forward end of which projects into a bracket 25 which is secured to the inner surface of the buffer member 20 by means of rivets 26. The bracket member 25 is provided with a centrally disposed lug 27 having a bearing opening therein, and the side walls 28 of such bracket are also provided with openings. An annular block 29 is fitted in the end of the stem 24, and such block is also provided with a bore. Extending through the portions 28, the tubular member 24, the block 29, and the lug 27, is a pivot pin 30, the arrangement being such that the tubular member 24 is pivotally connected to the buffer member 20. The tubular member is slidably mounted in the usual support 31 forming part of the end sill 32 of the car, a wear plate 33 being carried by the member 31 upon which the tubular member 24 slides. The rear end of the tubular member 24 is slotted on its opposite sides as indicated at 34, the slots 34 extending to a point adjacent the rear end of the member. The end sill 32 is provided with an opening 36 to permit reciprocation of the stem 24, and formed on the end sill 32 is a bracket 37, having an opening therein, and web 38 of the carrying portion 31 formed on the end sill 32 is also provided with an opening. Loosely disposed in the end of the tubular member is a block 40, having an opening therein corresponding in position with the openings just described, and all of such openings are aligned for the reception of the pivot pin 41 which preferably extends through the top wall of the platform as shown at 42. A coiled expansion spring 43 is disposed within the

tubular stem 24, the rear end of said spring bearing upon the block 40 and the forward end of said spring bearing upon the block 29. In operation during buff, the buffer member 20 is driven inwardly compressing the center compression resisting means 12 through the medium of the center stem 17. During the operation, the side stems 24 are also driven inwardly, and due to the presence of the slots 34 therein, each stem moves relatively to the pivot pin and block 40, resulting in compression of the spring 43 thereagainst. When the pressure is relieved upon the buffer member, each stem 24 is permitted to resume its original position under the influence of the spring 43.

By the above described arrangement it will be noted that the entire mechanism of the side stems is disposed in front of the 20 end sill 32, and this condition is rendered possible by shortening the stems 24 by providing a tubular arrangement which contains the spring elements. In ordinary constructions the side stems extend to the rear 25 of the end sill, and the spring is mounted on the stem to the rear of the end wall, necessitating an additional bearing for the rear extremity of the stem, and this arrangement sets up a disagreeable noise due to its 30 construction, which feature, as well as the excessive length of the stem is eliminated by my invention. In addition it should be noted that the arrangement described provides a hollow tubular side stem which is 35 pivotally connected to the buffer member, and pivotally and slidably connected to the end sill, whereby a very flexible arrangement is provided which permits pivotal movement of the buffer member when the 40 car is on a curve.

While I have herein shown and described what I now consider the preferred manner of carrying out the invention, the same is merely illustrative, and I contemplate all 45 changes and modifications which come within the scope of the claims appended hereto.

I claim:

1. In a buffing mechanism of the character described, the combination with the end platform of a car, provided with an abutment on its underframe; of a buffer member associated with said platform; longitudinal- 50 ly movable side stems slidably supported intermediate their ends by portions of said underframe, and having pivotal connection with said buffer member and with said underframe; and resilient means associated with said stems and interposed between said buffer member and said abutment.

2. In a buffing mechanism of the character described, the combination with the end sill of a car; of a buffer member; side stems 55 slidably supported intermediate their ends, and having slideable and pivotal connection with said end sill; and resilient means asso-

ciated with said stems and adapted to bear against said end sill and said buffer member.

3. In a buffing mechanism of the character described, the combination with the end 70 platform of a car provided with an abutment on its underframe; of a buffer member; tubular side stems connecting said buffer member with said underframe; and resilient means disposed within said tubular members 75 and normally urging said buffer member away from said abutment.

4. In a buffing mechanism of the character described, the combination with the end platform of a car provided with an underframe; 80 of a buffer member associated with said platform; and side stems, each of which has one end pivotally connected to the buffer member, and the other end pivotally and slidably connected to the underframe of 85 said platform; and resilient means associated with said stems for urging said buffer member outwardly from said platform.

5. In a buffing mechanism of the character described, the combination with the end 90 platform of a car provided with an underframe; of a buffer member; tubular side stems, each of which has one end pivotally mounted on a pin carried by said buffer, and the opposite end pivotally and slidably 95 mounted on a pin carried by said underframe; and resilient means disposed in said tubular members, and arranged to react against said pivot pins.

6. In a buffing mechanism of the character 100 described, the combination with the end platform of a car and the end sill thereof; of a buffer; a center stem associated with center compression resisting means and having its outer end bearing on said buffer 105 member; and tubular side stems, each of which has one end pivotally connected to a pivot pin secured to said buffer member, and the other end pivotally and slidably connected to a pivot pin mounted on means 110 carried by said end sill; bearing blocks closing the ends of said tubular stems and mounted on said pivot pins; and resilient means disposed in said tubular members and bearing upon the blocks associated with said 115 pivot pins.

7. In a buffer mechanism for passenger cars having an end platform underframe, the combination with a buffer plate; of a center stem; and side stems, each side stem 120 being connected to the buffer plate and slidably and pivotally connected to the platform underframe.

8. In a buffer mechanism for passenger cars, having an end platform casting, the 125 combination with a buffer plate; of a center stem; and side stems, each side stem being pivotally connected to the buffer plate and slidably connected to the platform casting, each said side stem being of tubular forma- 130

tion and having a spring disposed therein.

9. In a buffering mechanism, the combination with the underframe of a railway car; of a buffer; and tubular side stems, each of

6 which has one end pivotally connected to a pivot member secured to said buffer, and the other end pivotally connected to a pivot member mounted on said underframe, one of said pivotal connections permitting lon-

gitudinal movement of the stem; and resilient means disposed within said tubular side stems and normally urging the buffer outwardly.

In witness that I claim the foregoing I have hereunto subscribed my name this 16th 15 day of February 1925.

GEORGE E. COUTANT.
